UNITED STATES PATENT OFFICE.

HARRY J. FARRINGTON, OF JAMAICA PLAIN, MASSACHUSETTS, ASSIGNOR TO FARRINGTON MANUFACTURING COMPANY, OF JAMAICA PLAIN, MASSACHUSETTS, A CORPORATION OF MAINE.

HINGED BOX.

Application filed January 4, 1923. Serial No. 610,690.

To all whom it may concern:

Be it known that I, HARRY J. FARRINGTON, a citizen of the United States, and resident of Jamaica Plain, county of Suffolk, and State of Massachusetts, have invented an Improvement in Hinged Boxes, of which the following description, in connection with the accompanying drawing, is a specification, like characters on the drawing representing like parts.

This invention relates to a box comprising a body section and a cover section hinged together and provided with a spring construction by means of which the sections are retained yieldingly either in closed or open position. The invention is particularly useful in connection with the more or less ornamental boxes employed for the preservation and display of articles of jewelry and similar objects.

The object of the invention is to provide a spring hinge construction which shall permit the body and cover sections to be made as shallow as possible and consequently the box as a whole as thin as possible.

The object of the invention is further to provide a construction which shall reduce the cost of manufacturing the box both by reducing the amount of material required in the box, in covering the box, and in lining the box and by reducing the amount of labor and the number of tools or machines and operations required.

The object of the invention is further to provide a construction in which the spring element of the hinge may readily be removed and replaced in the construction and repair of the box.

The object of the invention is further to provide a construction in which the spring element of the hinge shall interfere as little as possible with the lining features of the box.

These and other objects and features of the invention will appear more fully from the accompanying description and drawings and will be particularly pointed out in the claims.

While the invention is useful in a wide variety of boxes adapted for a wide variety of purposes it is particularly useful in connection with more or less ornamental type of jewelry box made of sheet metal provided with an exterior covering and lined and

padded for the preservation and display of articles of jewelry or similar objects. Such a form of box is, therefore, illustrated in the drawings in connection with a preferred form of the invention.

In the drawings—

Fig. 1 is a view in central vertical cross section of a complete jewelry box embodying a preferred form of construction of the invention with the body and cover sections shown in open position;

Fig. 2 is a top plan view with portions broken away of a part of the box shown in Fig. 1;

Fig. 3 is a detail enlarged and in perspective of the hinge portion of the construction shown in Figs. 1 and 2 with the position of the spring when about to be removed or replaced indicated in dotted lines;

Fig. 4 is a view similar to Fig. 3 showing the hinge in operative position;

Fig. 5 is a detail in vertical cross section taken through the spring in Fig. 4;

Fig. 6 is a view similar to Fig. 5 with the parts in the position assumed when the body and cover sections are in closed position.

The box essentially comprises a hollow body section and a hollow cover section. Preferably these sections of the box are formed by stamping out sheet metal into the required shape. As illustrated both sections are of rectangular shape and, in the particular form illustrated, substantially square. The body section presents the bottom 1 and the upstanding or vertical side walls 2. The cover section is of similar shape and construction excepting that in the form illustrated the top 3 of the cover is convex with the side walls 4 vertical as in the case of those of the body section.

The body and cover sections are hinged together and it is found desirable, especially in this general type of box, for economy in manufacture and in order to secure a smooth and pleasing exterior of the box to make the hinge element separate and secure it to the box section.

The hinge member comprises a pair of flat leaves 5 and 6 united by a pintle 7. This hinge member is secured inside of the box, the leaves 5 and 6 being secured respectively to the side walls 4 and 2 of the cover and bottom sections. These parts are preferably secured in place by tabs 8 of the

- metal of the cover and body sections struck out inwardly and carried through apertures 9 in the hinge leaves and bent back against the leaves. This forms a very firm construction, leaves the exterior surface of the side walls of the cover and box sections flat and smooth to receive the covering material and throws the pintle and hinged connection of the leaves into the box interior.
- 10 The spring construction by means of which the cover and body sections of the box are yieldingly held in either open or closed position involves a spring operating upon the principle of that disclosed in the 15 patent to Nevelson #743,747 granted Nov. 10, 1903. Such a spring 10 consists of a resilient metal strip curved in the direction of its length and having the hooked ends 11. These hooked ends engage over the edges 20 of the leaves of the hinge and the construction is such that when the box sections are in closed positions as shown in Fig. 6 the tension in the spring due to its curved formation tends to draw the hooked ends together and thus hold the box sections closed. When the box sections are separated and swung to open position the spring expands and again contracts to hold the sections in open position as shown in Fig. 5 with the 25 body of the spring preferably in contact with the middle of the hinge so as to limit the opening movement.
- It is very desirable in this type of box that the body and cover sections shall be as 30 shallow as possible and the whole box as thin as possible. With the body of the box thus shallow the article of jewelry or other object supported therein is held up in plain view and readily accessible thus giving a 35 pleasing display effect. The depth of the body and cover sections of the box is determined by the depth of the side walls and the depth of these side walls is determined by the width of the leaves of the hinge.
- 40 But there is a limit to the width of the leaves which is determined by the width of the tabs 8 and apertures 9. These cannot be reduced beyond a certain point without 45 weakening the box structure.
- 50 As heretofore constructed it has been necessary to hook the spring 10 over the outer edges of the hinge leaves and consequently to place the bottom 1 of the body section and the top 3 of the cover section 55 at a substantial distance from the outer edges of the hinge leaves in order to provide room for the hooked ends of the spring and for the expansion and contraction of the 60 spring.
- 60 In the present invention the leaves of the hinge are provided at their outer edges with recesses formed by cutting away as shown at 12 the metal of the hinge. These recesses are preferably formed at points intermediate the length of the hinge. To pro-
- vide for the ready insertion and removal of the hinge additional or auxiliary recesses are formed in the leaves of the spring adjoining the main recesses as indicated at 13 and these auxiliary recesses are much deeper than the main recesses 12. Both recesses should be of a width at least that of the spring 10. The formation of these recesses in the leaves of the spring does not in any way weaken or injure the spring because 70 they are formed between the tabs 8 or other means provided for securing the spring to the box sections.
- The spring when in operative position engages the hinge leaves with its hooked ends 80 11 at the main recesses 12 as shown in detail in Figs. 4, 5 and 6. These main recesses are of such depth that a very short spring is sufficient. Consequently there is no engagement of the ends of the spring 85 with the bottom 1 of the body or the top 3 of the cover section at any time or, in other words, the spring is at all times within the outer edges of the leaves. Furthermore owing to the reduced length of the spring 90 its movement toward the center of the box or away from the pintle and back again is comparatively slight. Both of these features have a very appreciable effect upon the construction and appearance of the lining. 95
- Not infrequently the springs become broken or injured. The provision of the auxiliary recesses 13 enables the spring readily to be removed and replaced. To put a new spring in position it is only necessary to place the spring in alignment with the auxiliary recesses 13 as shown in Fig. 3 and then slide it endwise into its operative position in the main recesses 12 as shown in Fig. 4. By the opposite operation it is 100 removed with equal facility.
- Boxes of this character are usually covered on the exterior with a suitable covering material such as velvet, cloth, other textile material, leather, etc. Such a covering is shown at 14 extending over the entire exterior of both sections and carried back over the interior of the side walls except usually where the leaves of the spring are fastened to the side walls. The body section is usually provided with what is known as a satin collar 15 usually in the form of a strip of cardboard covered with satin and fitted in against the inner periphery of the 110 side walls. A protecting strip 16 of satin or suitable material usually overlies the hinge and extends down into the body section and up into the cover section. A pad is frequently mounted in the body section to support the article of jewelry or other object. Such a pad comprises a stiff cardboard base 17 having thereon padding material 18 and the whole covered by a suitable 115 satin or other covering 19. This pad fits closely within the body section and is usu-
- 120 125 130 135

ally glued in place. Owing to the extreme shallowness of the body section permitted by reason of the small size of the spring it is unnecessary to cut out or fit the edge 5 of the pad about the spring and the pad can consequently be made of the same shape as the interior of the body section. Thus the same die can be used in making the base of the pad at whichever side of the 10 body the cover be hinged.

The cover section is frequently provided with a puff formed by a loose piece of satin or other material 20 having its edges carried about a strip of cardboard 21 and the 15 whole thing snapped into place against the side walls of the cover leaving the material 20 to fit in toward the top of the cover. The slight movement of the spring provided with this invention does not interfere with 20 or injure the puff and requires no particular construction of the puff to fit over the spring.

The invention thus provides a construction which enables the entire box to be made 25 as shallow as possible and each section of the box to be of the minimum depth permitted by the use of the desirable form of the hinge construction. The cost of manufacture is reduced because less covering material is required, the cost and labor in providing material beneath the pad is eliminated, fewer dies are required in the manufacture of the pads and linings to fit the box and strain and wear upon the pad and lining 30 is eliminated. The invention for this and other reasons results in an extremely satisfactory form of box.

Having thus described the invention what is claimed as new and desired to be secured 40 by Letters Patent, is:

1. A box comprising hollow body and cover sections, a hinge having its leaves secured respectively to the said body and cover sections with the outer edge of each

leaf presenting a recess located between 45 points at which the leaf is secured to its section, a spring consisting of a resilient metal strip curved in the direction of its length, hooked at its ends, engaging the hinge leaves at the said recesses with its 50 hooked ends so as at all times to be within the outer edges of the leaves, and acting to hold the body and cover sections in either open or closed position and the outer edge of each leaf presenting an auxiliary recess 55 deeper than and adjoining the main recess, whereby the spring may readily be placed in, or removed from, operating position by sliding out from or into the auxiliary recesses and into or from engagement with 60 the leaves at the main recesses.

2. A box comprising hollow body and cover sections each presenting flat vertical side walls, a hinge having its leaves secured respectively to the said side walls of 65 the body and cover sections with the outer edges of the leaves located closely adjacent to the bottom of the body and the top of the cover sections respectively and with the outer edges of the leaves presenting recesses, and a spring consisting of a resilient metal strip curved in the direction of its length, hooked at its ends, engaging the hinge leaves at the said recesses with its hooked ends 70 so as at all times to be within the outer edges of the leaves, and acting to hold the body and cover sections in either open or closed position, and auxiliary recesses in the said outer edges of the hinge leaves deeper than 75 and adjoining the main recesses, whereby the spring may readily be placed in, or removed from, operative position by sliding out from or into the auxiliary recesses and into or from engagement with the leaves at 80 the main recesses.

In testimony whereof I have signed my name to this specification.

HARRY J. FARRINGTON.
